F. A. NEWHALL,
LOCK CONSTRUCTION,
APPLICATION FILED DEC. 13, 1919.

1,351,117.

Patented Aug. 31, 1920.

UNITED STATES PATENT OFFICE.

FREDERICK A. NEWHALL, OF NEW YORK, N. Y.

LOCK CONSTRUCTION.

1,351,117.

Specification of Letters Patent. Patented Aug. 31, 1920.

Application filed November 13, 1919. Serial No. 344,530.

To all whom it may concern:

Be it known that I, FREDERICK A. NEWHALL, a citizen of the United States, and residing at New York, in the county of New York and State of New York, have invented certain new and useful Improvements in Lock Constructions, of which the following is a specification, such as will enable those skilled in the art to which it appertains to make and use the same.

This invention relates to lock constructions and particularly to devices of this class designed for use in locking doors or other swinging or moving members; and the object of the invention is to provide a supplemental lock member which coöperates with the lock usually employed and is operated thereby; a further object being to provide a supplemental lock which is constructed of comparatively strong material and which coöperates with the lock usually employed to prevent the forcing of the door or other member in connection with which the lock mechanism is employed; and with these and other objects in view the invention consists in a lock construction of the class specified which is simple in construction and operation and efficient in use and constructed as hereinafter described and claimed.

The invention is fully disclosed in the following specification, of which the accompanying drawing forms a part, in which the separate parts of my improvement are designated by suitable reference characters in each of the views, and in which:

Figure 1 is an inside view of a part of a door and door frame and showing my improved lock construction attached thereto;

Fig. 2 a partial section on the line 2—2 of Fig. 1;

Fig. 3 a partial section on the line 3—3 of Fig. 1; and,

Fig. 4 a partial section on the line 4—4 of Fig. 3, with parts in a different position.

In Figs. 1 and 2 I have indicated at 5 a part of a door frame and at 6 a part of a door which operates in connection therewith. In Fig. 1 of the drawing, 7 represents the usual lock mechanism having a latch and lock bolt 8 operated by a suitable key or a knob 9.

The above construction is old and forms no part of my invention, and in practice, I employ in connection with the lock 7 a supplemental locking mechanism 10, comprising a striking plate 11, which is ap-

proximately of angle-iron form, one flange 12 of which is secured to the door frame by screws 13 and the other flange 14 of which extends at right angles to the door frame. 60

The flange 14 of the striking plate 11 is provided adjacent to the lower end thereof with a rectangular aperture 15 in connection with which the latch and lock bolt 8 of the lock 7 operates, as clearly illustrated in Fig. 65

3. The top portion of the striking plate 11 is provided with a forwardly projecting yoke-shaped bearing 16 composed of top and bottom members 17 and 18. The member 18 is provided with a downwardly directed 70 sleeve bearing 19, the lower end portion of which is slotted on opposite sides as shown at 20 in Fig. 4. A bolt 21 is movably mounted in the sleeve 19 and is adapted to pass through the bearing 16, or an aperture 22 in 75 the top member 17 of said bearing as clearly illustrated in Fig. 3 of the drawing.

I also secure to the door 6, above the lock 7, a plate 23 having an inwardly and outwardly directed rectangular head 24 provided with an aperture 25, and the head 24 of the plate 23 is adapted to pass into the bearing 16 between the top and bottom members 17 and 18 thereof, as clearly shown in Figs. 1 to 3 inclusive, and the bolt 21 is 85 adapted to pass through the aperture 25 and the head 24.

Pivoted to the striking plate 11, or the flange 14 thereof as shown at 26 is a cam device 27 having a comparatively wide back 90 plate 28. The cam device 27 is adapted to move upwardly and downwardly in the slots 20 in the sleeve 19 and to move the bolt 21 upwardly in said sleeve. The cam device 27 and bolt 21 normally drop into their inoperative position as shown in Fig. 4 by gravity, in which position it will be seen that the back plate 28 of the cam device 27 closes, or partially closes, the aperture 15 in the flange 14 of the striking plate whereby when the bolt 8 passes through the aperture 15, by

releasing the knob 9, or in the operation of closing the door, the cam device 27 will be moved inwardly and upwardly into the position shown in Figs. 1 and 3, and the bolt 105 21 correspondingly moved upwardly from the position shown in Fig. 4 to that shown in Fig. 3. In this last operation it will also be apparent that the bolt 21 passes through the aperture 25 in the head 24 of the plate 23 and the door 6 will be locked in connection with the door frame 5 or the striking

plate 10 in two different places. The door may be opened by the insertion of a key in the lock 7, or by manipulating the knob 9 to withdraw the bolt 8, which operation permits the cam device 27 and bolt 21 to drop by gravity and the door may be opened.

It will be apparent that my improved lock construction will more securely lock the door 6 in connection with the door frame and will prevent, or materially complicate the breaking in of the door by the use of jimmies or other implements, and by constructing the plate 23 as well as the head 24 thereof and the bolt 21 and striking plate 11 of comparatively hard metal, the forcing of the door by a jimmy or other implement will almost be impossible without breaking away part of the door frame. By reason of the fact that the latch and lock bolt 8 is constructed of comparatively soft metal, the door is readily opened by force, in which operation the latch and lock bolt 8 bends or gives but by employing my improved supplemental lock in connection with the lock 7, the forcing or breaking in of the door is materially complicated, if not entirely obviated. It will be apparent that while I have shown certain details of construction for carrying my invention into effect that I am not necessarily limited to these details, and changes therein and modifications thereof may be made, within the scope of the appended claims, without departing from the spirit of my invention or sacrificing its advantages.

Having fully described my invention, what I claim as new and desire to secure by Letters Patent, is:—

1. The combination with a lock, of a supplemental lock comprising a striking plate secured to a stationary support, an apertured lock element movable into and out of engagement with said striking plate, a lock bolt movably mounted in the striking plate and adapted in one position thereof to pass through said lock element to secure in engagement with said striking plate, means operated by the latch bolt of the first named lock for moving said lock bolt into its operative position, and means whereby the withdrawal of said latch bolt will permit said lock bolt and the means for operating the same to move into inoperative position by gravity.

2. A door lock construction of the class described comprising a striking plate secured to the door frame, a lock device secured to the door and provided with a latch and lock bolt adapted to operate in connection with said striking plate, one end por-

tion of the striking plate being provided with a recess, a lock element secured to the door and adapted to operate in connection with the recess in said striking plate, a lock bolt mounted in and movable vertically in the striking plate and adapted to pass through the recess therein and through the lock element when in said recess, and a cam device pivoted to the striking plate in juxtaposition to that part thereof with which the latch and lock bolt operates, the cam member of said cam device being independent of and adapted to operate in connection with said lock bolt to move the same into operative position by said latch and lock bolt in the operation of closing the door.

3. A door lock construction of the class described comprising an approximately L-shaped striking plate adapted to be secured to the door frame and provided at one end portion thereof with a pair of members which extend at right angles to said striking plate and which form between the same a recess, the other end portion of the striking plate or one side thereof being provided with an aperture, a cam device pivoted to the striking plate adjacent to said aperture, one of the members in said pair being provided with a downwardly directed sleeve slotted to receive the cam member of said cam device, a bolt mounted to move vertically in said sleeve and through said pair of members, said bolt being moved into operative position by the cam member of said cam device, and a lock element secured to the door and adapted to operate in the recess between the members of said striking plate and in connection with which said bolt is adapted to operate.

4. A combination with a lock of a supplemental lock comprising a striking plate secured to a stationary support, an apertured lock element movable into and out of engagement with said striking plate, a lock bolt movably mounted in the striking plate and adapted in one position thereof to pass through said lock element to secure the same in engagement with said striking plate, and means independent of said lock bolt and operated by the latch bolt of the first named lock for moving said lock bolt into its operative position.

In testimony that I claim the foregoing as my invention I have signed my name in presence of the subscribing witnesses this 9th day of December, 1919.

FREDERICK A. NEWHALL.
